UNITED STATES PATENT OFFICE.

DARWIN C. BOYCE, OF QUINNIMONT, WEST VIRGINIA, ASSIGNOR OF ONE-HALF TO J. M. CLARK, OF SAME PLACE.

CRADLE-DUMP.

SPECIFICATION forming part of Letters Patent No. 560,567, dated May 19, 1896.

Application filed August 16, 1895. Serial No. 559,517. (No model.)

To all whom it may concern:

Be it known that I, DARWIN C. BOYCE, a citizen of the United States, residing at Quin-
nimon, in the county of Fayette and State of
West Virginia, have invented certain new and
useful Improvements in Cradle-Dumps, of
which the following is a specification, refer-
ence being had therein to the accompanying
drawings.

10 My invention relates to an improvement in
cradle-dumps, and includes automatic means
for stopping and releasing cars.

15 The invention consists in the improved de-
vices and combination of devices hereinafter
more fully described and particularly claimed.

20 In the accompanying drawings, Figure 1 is
a plan view of the dump, showing one set of
the wheels of a car in position against the
stop-bars. Fig. 2 is a side elevation of the
same, showing at the right-hand side the
25 means operated by the approaching car for
releasing the car already on the dump. Fig.
3 is an end elevation, partly in section, of
Fig. 1. Fig. 4 is a plan view of the treadle
and dump.

25 In the accompanying drawings the frame
of the dump is shown at A, and consists of a
series of cross-beams connected to each other
at the ends, these cross-beams being arched in
the center, as shown at 1, and their ends be-
30 ing connected by beams 2. Centrally through
these beams passes a rocking shaft u, by
which the frame is tilted and the load dumped.
The frame carries tracks 3, on which the
35 wheels of the cars run, and a protecting-frame
4 (shown clearly in Figs. 2 and 3) extends up
above the position of the car-wheels, so as to
hold the same securely during the dumping
of the car. This frame is composed of angu-
40 lar metal plates bolted to the cross-beams at
the ends thereof, as shown at 5, Fig. 3, and
the upper parts of these plates overhang the
tread of the wheels, as shown at 6, a supple-
mental angle-plate 7 depending from the over-
45 hanging part 6, so as to prevent any undue
lateral movement of the car.

50 In order to limit the movement of the in-
coming car and to stop it at the proper point
on the dump and in exactly the same place
each time, I provide stop-arms g, projecting
from a rock-shaft g', which has its bearings

in blocks on the frame, as shown in Figs. 1
and 2. These stop-arms project into the path
of the wheels of the car, and are provided
with curved faces, as shown in Fig. 2, which 55
conform to the periphery of the wheels, and
when these arms are in position the car is
stopped by them. After the car has been
dumped it is necessary, however, to release it
and to allow it to proceed on for another load, 60
and to provide for this it is necessary to re-
move the stop-arms from the path of the
wheels. To this end the rocking shaft g' on
each side has a depending arm f, and from
each of these arms extends a bell-crank lever 65
b, pivoted at the angle to brackets b', project-
ing from the frame, as shown in Fig. 1. The
movement of these bell-crank levers in one
direction or the other will operate the shafts
70 g', with the effect of moving the stop-arms
into or out of line with the wheels of the car.
The ends d of the bell-crank levers are con-
nected to a central rod e, which carries a col-
lar fixed to it, as shown at l, and encircling
75 the rod e, and between the collar and one of
the cross-beams is a spiral spring k, which
has the tendency to keep the rod e pressed to
the right, as in Fig. 1, which, through the
connections described, keeps the stop-arms
80 normally in the path of the wheels.

As the cars are constantly going and com-
ing it is desirable that some provision be
made for the automatic operation of these
stop-arms, so that at the proper time they
will be moved out of line to release the car 85
on the dump and to make room for the incom-
ing car, and I have provided for such auto-
matic action by the means now to be de-
scribed and clearly shown in the right of Fig.
2. In proximity to the rails at the entrance 90

to the dump-frame I arrange a treadle-plate
n on one side, this being adapted to receive
the flanges of the wheels and to be operated
thereby. This plate is supported by links
p p, pivoted at their lower ends to the frame- 95
work supporting the rails, (not shown,) so as
to have movement under pressure, and the
plate is kept elevated by means of a link o,
connected at one end to the plates, and con-
nected at the opposite end to an arm p', pro- 100
jecting from the shaft q. This shaft has an
arm p" projecting in a direction opposite to

the arm p' , and this arm is weighted, as at v . The tendency is to keep the plate n pressed up. A lever r projects vertically from the shaft q and is connected by a link s to a lever t . This lever t bears directly against the end of the rod e , to which the bell-cranks are connected for operating the stop-arms, and the effect is that as soon as the incoming car reaches the treadle-plate n this plate is depressed, depressing the link o against the pressure of the weight v , which rocks the lever r and forces the lever t forward through the link s . The lever t , contacting with the rod e , forces the rod forward against the tension of the spring k , and through the bell-cranks throws the stop-arms to one side, thus leaving the first car free to be pushed forward by the second as it enters the dump. Before the rear wheels of the second car have left the treadle-plate n the rear wheels of the first car will have passed beyond the position of the stop-arms, and as soon as the rear wheels of the second car leave the treadle-plate n the weight v restores the parts to normal position, the spring k forces the rod e outward, and the stop-arms are thrown into position to stop the second car. The rod e has a collar l^2 , which limits its outward movement, and this serves to also limit the inward movement of the stop-arms. The arching of the cross-beams intermediate of their length places the fulcrum on which the platform tilts the minimum distance from the center of the load, and thereby decreases the lever-

age necessary to dump the car, and also makes possible the use of unusually light counter-balances.

What I claim is—

1. In combination, a dump-frame comprising the longitudinal beams supporting the rails, the cross-beams having the arched central portions, and the rocking shaft supported in said arched portions, whereby said shaft, which forms the fulcrum of said frame, will be in juxtaposition to the load, said load comprising a car adapted to be emptied parallel to said cross-beams, thereby reducing the leverage necessary to tilt said frame to a minimum, substantially as described. 35

2. In combination, the dump-frame, the track leading thereto, the stop-arms, the sliding rod for operating the same, the treadle-plate arranged on the inner side of said track, the rocking shaft, the connection between said plate and shaft for operating the same, the weighted arm extending from said shaft, a vertical lever pivotally supported at its lower end, a lever extending from said shaft parallel to the first lever and the link connection between the upper ends of said levers 55 whereby said rod is operated on the depression of said treadle, substantially as described. 60

In testimony whereof I affix my signature in presence of two witnesses.

DARWIN C. BOYCE.

Witnesses:

C. W. ROSS,
W. V. CONARD.
